UNITED STATES PATENT OFFICE

MAURICE P. WHITNEY, OF ELMIRA, NEW YORK, ASSIGNOR TO ECLIPSE MACHINE COMPANY, OF ELMIRA, NEW YORK, A CORPORATION OF NEW YORK

ENGINE STARTER

Application filed December 5, 1923. Serial No. 678,733.

My invention relates to means for starting an engine such as an internal combustion engine and pertains more particularly to the drive or transmission which is located between a prime mover such as an electric motor and a member of the engine to be started such as a flywheel thereof. The object of my invention is to provide novel and efficient means for preventing any undue strain upon or injury to the parts of the drive in case the pinion is in mesh with the flywheel when the engine is rotating backwardly as in the event of back fire, and also for preventing the meshing of the driving member or pinion of the drive when the engine is so rotating or moving backwardly. My present invention is an improvement upon that heretofore made by me as described and claimed in an application filed 20 February 3, 1923, Serial No. 616,669.

In the drawings Fig. 1 is a sectional elevation of a starter system embodying my invention; Fig. 2 a similar view but illustrating the cranking position of the drive; Fig. 25 3 a similar view but illustrating the relative position of the drive parts and the directions of rotation thereof when the flywheel is rotating backwardly and the pinion is in contact but not in mesh therewith; and 30 Figs 4 and 5 sections on the corresponding section lines of Figs. 2 and 3 respectively.

In the present instance I have illustrated my invention in connection with the well-known Bendix drive of the so-called free pinion type in which the driving member or pinion is made in two parts, one the pinion proper and the other the control member or nut, but it will be understood that I have so disclosed my invention here-40 in for the sake of a clear and definite description and that the same, in its broader aspect, is applicable to drives having different forms of driving members. It will also be understood that my invention while 45 shown in connection with the direct drive and also outboard type of drive is also applicable to the indirect type and the inboard type of drive.

In the particular embodiment of my invention as illustrated in the drawings the

electric motor 1 has an extended armature shaft 2 on which is mounted a Bendix drive of said free pinion type but having modifications for the embodiment of my present invention. This drive is provided with release means cooperating between the two parts of the driving member for the purpose of automatically disconnecting the driving member or pinion from the flywheel in the event of backfire and also for the purpose 55 of preventing meshing of the pinion with the flywheel in the event of backfire or back rock.

Describing the embodiment of my invention as herein shown, the drive is detachably mounted upon the driving or armature shaft 2 whose outer end is supported in a bearing formed on a bracket 3 which projects forwardly from a casing 4 that is attached to the motor frame in suitable 60 manner as by means of the screws 5. This casing is also attached by means of the screws 6 to the flywheel casing 7 of the engine, within which rotates the flywheel 8.

The drive comprises a hollow screw shaft 75 9 having a screw threaded portion 10 and mounted on the armature shaft 2 and driven thereby through the driving head 11, drive spring 12 and driven head 13 of the screw shaft. Upon the screw shaft there is mounted the driving member which is here 80 in two parts, the pinion proper marked 14 and the control member or nut marked 15. The pinion which has a smooth bore is mounted loosely upon the screw threads, and, 85 when moved longitudinally by the nut, it is adapted to operatively engage the teeth 16 of the flywheel. The nut 15 is threaded upon the screw shaft and is adapted to move longitudinally thereof and to rotate therewith. The nut in its advance movement longitudinally of the screw shaft contacts the pinion and moves the latter longitudinally into mesh with the flywheel for engine 90 cranking purposes. The release means 95 which constitute the novel feature of my invention is interposed between the pinion and the nut and cooperates with both of them for the purposes hereinbefore specified. Describing the particular embodiment 100

of such release means as herein shown, the pinion is provided with a disk or flange 17 to whose inner face there is attached in suitable manner as by means of the screws 18 a beveled gear 19. The nut 15 is likewise provided with a flange 20 to whose outer face is secured by means of the screws 21 a beveled gear 22. The two gears 19 and 22 are similar but opposed. Surrounding the control nut and its flange and the pinion flange is a cage 23 which is in turn mounted to rotate within a casing or sleeve 24 but in one direction only. For this latter purpose a one-way clutch is interposed between the periphery of the cage and this casing 24 such clutch here comprising the series of balls 25 arranged in the inclined peripheral grooves 26 in the cage.

Suitably mounted in the cage are two 20 studs 27 which are arranged diametrically opposite each other and on whose inner ends are loosely mounted for rotation small beveled pinions 28 which are in constant mesh with the beveled gears 19 and 22. 25 Friction is provided in suitable manner between these beveled pinions and their studs for a purpose hereinafter mentioned, such friction being herein provided by means of the compression springs 29 interposed between the cage and the pinions and pressing the latter against the enlarged inner heads of the studs.

The cage not only surrounds the nut and its pinion and also the pinion flange 17 but 35 also constitutes an assembly therewith and has means for limiting the displacement or separation of the nut and pinion from each other, for which purpose the cage is provided with an inwardly directed radial 40 flange 30 and an end ring 31 screwing upon the outer end of the cage and provided with an inwardly directed flange 32 extending over the pinion flange 17.

The casing or sleeve 24 is so mounted 45 within the casing 4 as to float somewhat therein rotarily to which end it is secured rigidly at one point by means of the screw 33 and yieldingly by means of the screw 34 which is here diametrically opposite the 50 other screw and which has a pin and slot connection with the sleeve 24, such pin being the inner end 35 of the screw 34 and the slot being the slot 36 in the sleeve 24 as shown more particularly in Fig. 5.

55 Describing a cycle of operation and beginning with the parts in their normal position in Fig. 1, when the starting motor switch is closed and the armature shaft 2 is rotated, the screw shaft 10 is likewise 60 rotated with the result that the entire assembly including the pinion proper, the nut and release means are automatically advanced longitudinally of the screw shaft, the clearance space 37 between the outer 65 end of the nut and the pinion or rather the

interposed web of the beveled gear 19 being first taken up, it being understood that there is sufficient play between the beveled pinions and the beveled gears to permit of this slight movement. The pinion is thereby brought into mesh with the flywheel as shown in Fig. 2. This advance or longitudinal movement of the assembly is arrested by contact of the pinion or rather the interposed ring 38 against the stop nut 39 whereby the pinion is clamped between such stop nut and the nut 15. The parts are now in cranking position and the entire assembly including the pinion and nut now partaking of the rotary movement of the screw shaft, the torque of the motor is transmitted to the flywheel and the engine is thereupon cranked.

When the engine starts on its own power the pinion will be demeshed in the well-known automatic manner inasmuch as the flywheel will rotate the pinion at a speed greater than the speed of the screw shaft. Due to the friction between the bevel pinions and the cage, these pinions are retarded as to rotation and the increased speed of the pinion 14 is thereby transmitted through the bevel gear 19, the bevel pinions 28 and the bevel gear 22 to the control nut. This assembly now rotates as a unit, the two bevel gears 19 and 22 rotating in the same direction. The nut is thereby screwed back along the screw threads until the pinion 14 is out of engagement with the flywheel. The parts are then restored to the normal position shown in Fig. 1, ready for another cycle of operation.

If, at the time that the starting motor switch is closed, the flywheel should be rotating or rocking backwards as shown by the arrow in Fig. 3, the assembly of pinion, nut and release means will be advanced longitudinally in the manner above explained until the pinion 14 comes into contact with the rotating flywheel. This pinion is thereupon set in rotation in the direction shown by its arrow in Fig. 3, whereby the beveled gear 19 is rotated in the same direction. Inasmuch as the cage 23 cannot rotate in the same direction as the beveled gear 19 because the one-way or over-running clutch holds it stationary in that direction, the beveled pinions will thereupon transmit the rotation of the beveled gear 19 to the beveled gear 22 which will thereby be rotated in a direction opposite to that of the beveled gear 19. The further result of this particular direction of rotation of the beveled gear 22 will be to rotate the control nut on the screw threads in the same direction as the screw shaft is rotated. Consequently the nut is screwed backwardly along the screw shaft and away from operative contact with the pinion 14 or the web of the beveled gear 19 connected therewith.

and the clamping action between such nut and the pinion is prevented. Consequently under the conditions above set forth it is impossible to mesh the pinion with the flywheel and strain upon or injury to the parts of the drive is thereby avoided.

In case of back firing of the engine during the time of cranking by the drive, that is with the pinion 14 in mesh with the flywheel, the release means will act to positively demesh the pinion from the flywheel, by reason of the backward rotation of the pinion and consequent action of the release means in the same manner as above explained in the event that the pinion merely comes into contact with the backwardly rotating flywheel as shown in Fig. 3. In the event of back firing during the time of cranking, the nut will thus be rotated in the same direction as the screw shaft is rotating and the entire assembly including the pinion 14 will be positively withdrawn out of mesh with the flywheel and clamping action between the nut and the pinion will be prevented, wherefore all strain upon and injury to the parts that might otherwise result will be avoided.

In this manner and by these means the backward rotation of the driving member or pinion which is caused by the backward rotation of the engine member or flywheel (which would drive the pinion at a speed greater than the screw shaft) is communicated to the control member or nut in such a way as to rotate such nut forwardly in the same direction as the rotation of the screw shaft, with the result of releasing the pinion from driving relation or contact with the engine member upon backward rotation of the latter and of destroying or preventing the driving relation between the nut and the pinion. This result is accomplished by the gearing interposed between the nut and the pinion for thus translating the backward rotation of the pinion into a forward rotation of the nut.

I claim:

1. An engine starter including a member of the engine to be started, a drive adapted to engage and drive such engine member, means surrounding such drive for preventing cranking engagement with the engine member upon backward rotation of the latter.
2. An engine starter including a member of the engine to be started, a drive adapted to engage and drive such engine member, and including a driving member mounted for longitudinal movement to engage the engine member and for rotary movement to drive it, and means surrounding the driving member for preventing cranking engagement with the engine member upon backward rotation of the latter.
3. An engine starter including a member

of the engine to be started, a drive adapted to engage and drive such engine member, means surrounding such drive for releasing the drive from engagement with the engine member upon backward rotation of the latter.

4. An engine starter including a member of the engine to be started, a drive adapted to engage and drive such engine member, and including a driving member mounted for longitudinal movement to engage the engine member and for rotary movement to drive it, and means surrounding the driving member for releasing the driving member from engagement with the engine member upon backward rotation of the latter.

5. An engine starter including a member of the engine to be started, a self-contained unitary drive having a single part for engagement with said engine member, said drive adapted to engage and drive such engine member and including means directly actuated by the engine member for disengaging the drive from such engine member when the latter becomes the driver in either direction of rotation.

6. An engine starter including a member of the engine to be started, a drive adapted to engage and drive such engine member and including a driving member mounted for longitudinal movement to engage the engine member and for rotary movement to drive it and actuated directly by the engine member in event of back-fire of the engine, and also including means actuated by said driving member for disengaging the driving member from the engine member when the latter becomes the driver in either direction of rotation.

7. An engine starter including a member of the engine to be started, a drive adapted to engage and drive such engine member and including a rotatable shaft and a driving member mounted thereon for longitudinal movement thereof and rotary movement therewith, and means surrounding the driving member for releasing the latter from the engine member upon backward rotation of the latter.

8. An engine starter including a member of the engine to be started, a drive adapted to engage and drive such engine member and including a rotatable driving member and a rotatable control member cooperating therewith, and means arranged concentric of the shaft for releasing the driving member from engagement with the engine member upon backward rotation of the latter.

9. An engine starter including a member of the engine to be started, a drive adapted to engage and drive such engine member and including a rotatable driving member and a rotatable control member cooperating therewith, and means for translating the backward rotation of the driving member

- into a forward rotation of the control member.
10. An engine starter including a member of the engine to be started, a drive adapted to engage and drive such engine member and including a rotatable driving member and a rotatable control member cooperating therewith, and means for translating the backward rotation of the driving member into a forward rotation of the control member, the last said means including means for preventing the rotation of the control member in one direction.
11. An engine starter including a member of the engine to be started, a drive adapted to engage and drive such engine member and including a rotatable driving member and a rotatable control member cooperating therewith, and means for translating the backward rotation of the driving member into a forward rotation of the control member, and including a one-way clutch cooperating with the control member.
12. An engine starter including a member of the engine to be started, a drive adapted to engage and drive such engine member and including a rotatable driving member and a rotatable control member cooperating therewith, and means arranged concentric of the shaft for releasing the driving member from engagement with the engine member upon backward rotation of the latter, and including a one-way clutch also arranged concentric of the shaft and cooperating with said control member.
13. An engine starter including a member of the engine to be started, a drive adapted to engage and drive such engine member and including a rotatable driving member and a rotatable control member cooperating therewith, and means for translating the backward rotation of the driving member into a forward rotation of the control member, said means surrounding said drive.
14. An engine starter including a member of the engine to be started, a drive adapted to engage and drive such engine member and including a rotatable driving member and a rotatable control member cooperating therewith, and means interposed between the two members for translating the backward rotation of the driving member into a forward rotation of the control member.
15. An engine starter including a member of the engine to be started, a drive adapted to engage and drive such engine member and including a rotatable driving member and a rotatable control member cooperating therewith, and means surrounding said two members and interposed between them for translating the backward rotation of the driving member into a forward rotation of the control member.
16. An engine starter including a mem-
- ber of the engine to be started, a drive adapted to engage and drive such engine member and including a rotatable driving member and a rotatable control member cooperating therewith, and means for translating backward rotation of the driving member into forward rotation of the control member including gearing interposed between the two members and adapted to rotate the control member forwardly when the driving member rotates backwardly.
17. An engine starter including a member of the engine to be started, a drive adapted to engage and drive such engine member, and comprising a rotatable driving member and a rotatable control member cooperating therewith, and means for translating the backward rotation of the driving member into forward rotation of the control member including opposed gears on the two members respectively and pinions located between the gears and cooperating therewith.
18. An engine starter including a member of the engine to be started, a drive adapted to engage and drive such engine member, and comprising a rotatable driving member and a rotatable control member cooperating therewith, and means for translating the backward rotation of the driving member into forward rotation of the control member including opposed gears on the two members respectively, pinions located between the gears and cooperating therewith, and a cage for said pinions.
19. An engine starter including a member of the engine to be started, a drive adapted to engage and drive such engine member, and comprising a rotatable driving member and a rotatable control member cooperating therewith, opposed gears on the two members respectively, pinions located between the gears and cooperating therewith, and a cage for said pinions rotatable in one direction only.
20. An engine starter including a member of the engine to be started, a drive adapted to engage and drive such engine member, and comprising a rotatable driving member and a rotatable control member cooperating therewith, opposed gears on the two members respectively, pinions located between the gears and cooperating therewith, a rotatable cage for said pinions, and a non-rotatable casing which surrounds the cage and with which the cage has a one-way connection.
21. An engine starter including a member of the engine to be started, a drive adapted to engage and drive such engine member, and comprising a rotatable driving member and a rotatable control member cooperating therewith, opposed gears on the two members respectively, pinions located between the gears and cooperating therewith, a ro-

tatable cage for said pinions, a non-rotatable casing which surrounds the cage, and a one-way clutch between the cage and casing.

22. An engine starter including a member of the engine to be started, a drive adapted to engage and drive such engine member, and comprising a rotatable driving member and a rotatable control member cooperating therewith, and means for translating the backward rotation of the driving member into forward rotation of the control member including opposed gears on the two members respectively, pinions located between the gears and cooperating therewith, and a cage for said pinions having means for limiting the amount of longitudinal separation of the two members.

23. An engine starter including a member of the engine to be started, a drive adapted to engage and drive such engine member, and comprising a rotatable driving member and a rotatable control member cooperating therewith, and means for translating the backward rotation of the driving member into forward rotation of the control member including opposed gears on the two members respectively, pinions located between the gears and cooperating therewith, and a cage in which said pinions are mounted and which surrounds said gears and the control member and a portion of the driving member, said cage having means to limit the longitudinal separation of said two members.

24. An engine starter including a member of the engine to be started, a drive adapted to engage and drive such engine member, and comprising a rotatable driving member and a rotatable control member cooperating therewith, and means for translating the backward rotation of the driving member into forward rotation of the control member including opposed gears on the two members respectively, pinions located between the gears and cooperating therewith, and a cage in which said pinions are mounted and which surrounds said gears and the control member and a portion of the driving member, said cage having at its opposed ends radial inwardly directed flanges which are contacted by said two members to limit their longitudinal separation.

25. An engine starter drive comprising a pinion adapted to engage and drive a member of the engine to be started, a control member cooperating with the pinion to advance it into such engagement and cause it to be rotated, and means for translating the backward rotation of the driving member into a forward rotation of the control member.

26. An engine starter drive comprising a pinion adapted to engage and drive a member of the engine to be started, a control

member cooperating with the pinion and adapted to establish its driving relation, and means actuated by the backward movement of the pinion for releasing such driving relation and withdrawing the control member from operative position.

27. An engine starter drive comprising a pinion adapted to engage and drive a member of the engine to be started, a control member cooperating with the pinion and adapted to establish its driving relation, and means actuated by the backward movement of the pinion for releasing such driving relation and withdrawing the control member from operative position, said means including gearing between the pinion and the control member for rotating the latter forwardly when the pinion is rotated backwardly.

28. An engine starter drive including a rotatable shaft, a pinion loosely mounted thereon and adapted to be moved longitudinally thereof into engagement with a member of the engine to be started and to be rotated by such shaft, a nut mounted on the shaft for longitudinal movement thereof and rotary movement therewith and adapted to move the pinion longitudinally into such engagement and to clamp it into rotative relation with the shaft, and means for translating the backward rotation of the pinion into forward rotation of the nut including gears mounted on the pinion and nut, and pinions meshing with the gears and disposed intermediate thereof.

29. An engine starter drive including a rotatable shaft, a pinion loosely mounted thereon and adapted to be moved longitudinally thereof into engagement with a member of the engine to be started and to be rotated by such shaft, a nut mounted on the shaft for longitudinal movement thereof and rotary movement therewith and adapted to move the pinion longitudinally into such engagement and to clamp it into rotative relation with the shaft, and means for translating the backward rotation of the pinion into forward rotation of the nut including oppositely disposed bevel gears secured to the pinion and nut respectively, and bevel pinions meshing with said gears and disposed intermediate thereof.

30. An engine starter drive including a rotatable shaft, a pinion loosely mounted thereon and adapted to be moved longitudinally thereof into engagement with a member of the engine to be started and to be rotated by such shaft, a nut mounted on the shaft for longitudinal movement thereof and rotary movement therewith and adapted to move the pinion longitudinally into such engagement and to clamp it into rotative relation with the shaft, said pinion and nut having radial flanges, and means for translating the backward rotation of the pinion

into forward rotation of the nut including oppositely disposed bevel gears secured to said flanges respectively, and bevel pinions meshing with said gears and disposed intermediate thereof.

31. An engine starter drive including a rotatable shaft, a pinion loosely mounted thereon and adapted to be moved longitudinally thereof into engagement with a member of the engine to be started and to be rotated by such shaft, a nut mounted on the shaft for longitudinal movement thereof and rotary movement therewith and adapted to move the pinion longitudinally into such engagement and to clamp it into rotative relation with the shaft, and means for translating the backward rotation of the pinion into forward rotation of the nut including oppositely disposed bevel gears secured to the pinion and nut respectively, a cage surrounding the gears and flanges, and bevel pinions mounted in the cage and meshing with said gears and disposed intermediate thereof.
32. An engine starter drive including a rotatable shaft, a pinion loosely mounted thereon and adapted to be moved longitudinally thereof into engagement with a member of the engine to be started and to be rotated by such shaft, a nut mounted on the shaft for longitudinal movement thereof and rotary movement therewith and adapted to move the pinion longitudinally into such engagement and to clamp it into rotative relation with the shaft, and means for translating the backward rotation of the pinion into forward rotation of the nut including oppositely disposed bevel gears secured to the pinion and nut respectively, bevel pinions meshing with said gears and disposed intermediate thereof, and means for applying resistance to the rotation of the bevel pinions.

33. An engine starter drive including a rotatable shaft, a pinion loosely mounted thereon and adapted to be moved longitudinally thereof into engagement with a member of the engine to be started and to be rotated by such shaft, a nut mounted on the shaft for longitudinal movement thereof and rotary movement therewith and adapted to move the pinion longitudinally into such engagement and to clamp it into rotative relation with the shaft, and means for translating the backward rotation of the pinion into forward rotation of the nut including oppositely disposed bevel gears secured to the pinions and nut respectively, bevel pinions meshing with said gears and disposed intermediate thereof, and means for applying frictional resistance to the rotation of the bevel pinions.

34. An engine starter drive including a rotatable shaft, a pinion loosely mounted thereon and adapted to be moved longi-

tudinally thereof into engagement with a member of the engine to be started and to be rotated by such shaft, a nut mounted on the shaft for longitudinal movement thereof and rotary movement therewith and adapted to move the pinion longitudinally into such engagement and to clamp it into rotative relation with the shaft, and means for translating the backward rotation of the pinion into forward rotation of the nut including oppositely disposed bevel gears secured to the pinions and nut respectively, bevel pinions meshing with said gears and disposed intermediate thereof, and springs for applying frictional resistance to the rotation of the bevel pinions.

35. An engine starter drive including a rotatable shaft, a pinion loosely mounted thereon and adapted to be moved longitudinally thereof into engagement with a member of the engine to be started and to be rotated by such shaft, a nut mounted on the shaft for longitudinal movement thereof and rotary movement therewith and adapted to move the pinion longitudinally into such engagement and to clamp it into rotative relation with the shaft, and means for translating the backward rotation of the pinion into forward rotation of the nut including oppositely disposed bevel gears secured to the pinion and nut respectively, a cage surrounding the gears and flanges, studs mounted in the cage radial thereof, and bevel pinions loosely mounted on the studs and meshing with the gears.

36. An engine starter drive including a rotatable shaft, a pinion loosely mounted thereon and adapted to be moved longitudinally thereof into engagement with a member of the engine to be started and to be rotated by such shaft, a nut mounted on the shaft for longitudinal movement thereof and rotary movement therewith and adapted to move the pinion longitudinally into such engagement and to clamp it into rotative relation with the shaft, and means for translating the backward rotation of the pinion into forward rotation of the nut including oppositely disposed bevel gears secured to the pinion and nut respectively, a cage surrounding the gears and flanges, studs mounted in the cage radial thereof, bevel pinions loosely mounted on the studs and meshing with the gears, and springs interposed between the cage and bevel pinions to apply frictional resistance thereto.

37. An engine starter including a motor having an extended armature shaft, a cylindrical casing secured to and extending from one end thereof and surrounding the shaft, a drive mounted on said shaft and adapted to establish driving connection between the motor shaft and a member of the engine to be started, said drive including a driving member and release means for releasing the

driving connection upon backward rotation of the engine member and the driving member, said release means including a cage, and means arranged between the cage and casing for preventing the rotation of the cage in one direction.

38. An engine starter including a motor having an extended armature shaft, a cylindrical casing secured to and extending from one end thereof and surrounding the shaft, a drive mounted on said shaft and adapted to establish driving connection between the motor shaft and a member of the engine to be started, said drive including a driving member and release means for releasing the driving connection upon backward rotation of the engine member and the driving member, said release means including a cage, and a one-way clutch between the cage and casing for preventing the rotation of the cage in one direction.

39. An engine starter including a motor having an extended armature shaft, a cylindrical casing secured to and extending from one end thereof and surrounding the shaft, a drive mounted on said shaft and adapted to establish driving connection between the motor shaft and a member of the engine to be started, said drive including a driving member and release means for releasing the driving connection upon backward rotation of the engine member and the driving member, said release means including a cage, a sleeve surrounding the cage and secured at one point of its periphery to the interior of the casing and free at other points, and a one-way clutch between the sleeve and cage for preventing the rotation of the cage in one direction.
